FUEL PUMP

Frank C. Mock, Montclair, N. J., assignor, by
mesne assignments, to Eclipse Aviation Cor-
poration, East Orange, N. J., a corporation of
New Jersey

Application October 11, 1932, Serial No. 637,341

9 Claims. (Cl. 103—203)

This invention relates to pumps and more particularly to liquid pumps adapted to meter and force fuel to the combustion chamber of an internal combustion engine.

5 The present application is a continuation in part of my co-pending application, Serial No. 546,122, filed June 22, 1931.

It has heretofore been suggested to construct multi-cylinder fuel pumps in a manner to have 10 an individual operating member or cam for each pump piston. In the usual construction of engine fuel pumps the amount of fuel forced at each stroke of the piston is small, and it is therefore difficult to construct a plurality of cams with 15 such accuracy as to eliminate objectionable variations in fuel charges between the individual engine cylinders. Unequal fuel charges produce unequal combustion pressures which cause engine vibration and generally unsatisfactory operation.

An object of the present invention is to provide a multi-cylinder fuel pump in which all the pistons are actuated by a single cam preferably arranged centrally of the fuel pump cylinders. In 25 this arrangement the same cam operates all of the pistons, and therefore variations in stroke are obviated.

Another object of the invention is to provide a compact multi-cylinder pump which is easy to 30 manufacture and in which the body portion may be formed of a light metal, such as aluminum, within which the individual pump cylinders, preferably constructed of steel, may be readily assembled.

35 Another object of the invention is to provide a fuel pump which is self-priming.

Another object of the invention is to provide a fuel pump in which occluded gases are readily eliminated from the cylinders.

40 Another object of the invention is to provide a fuel pump in which particles of foreign matter are ejected therefrom and returned to the main supply tank.

Another object of the invention is to provide a 45 fuel pump in which fuel leakage past the piston is returned to the supply tank without being subjected to pump pressure.

Another object of the invention is to provide a fuel pump which is vented to the supply tank 50 during the intake stroke, whereby occluded gases may be ejected from the cylinder during the intake cycle.

A feature of the illustrated embodiment of the 55 invention relates to an arrangement of pump cylinders around a central power driven cam which

operates the various pump pistons in sequence and is axially slidable on the shaft to vary the stroke of the pump piston at the will of the operator. The cylinders are preferably arranged parallel to the operating shaft, although not necessarily so, and a bell crank preferably provided with a spherical cam contacting surface is pivotally mounted on the pump housing for causing the cam to actuate the pistons. Each pump cylinder is preferably provided with a novel self-priming feature as well as means for eliminating occluded gases therefrom, which gases are directed to the outlet from a central supply chamber preferably fed by means of a pressure pump drawing fuel from the main tank. Means are also provided in the central supply chamber formed in the pump for straining the fuel and returning gases and dirt particles therefrom to the main tank.

Other objects and features of the invention will 20 be apparent from the following description of a preferred embodiment of the invention in connection with which reference may be had to the accompanying drawing in which.

Fig. 1 is a sectional view of the improved 25 pump, and a diagrammatic arrangement thereof for use on an engine, the engine cylinder and supply tanks being drawn to a somewhat smaller scale,

Fig. 2 is an enlarged perspective view of the 30 washer used to position the spring of the pump cylinder outlet valve for preventing accumulation of gases at the upper end of the spring, and

Fig. 3 is an end view of the operating cam, as 35 viewed on line 3—3 of Fig. 1.

Referring to the drawing, the fuel pump is provided with a housing 11 within which is an operating shaft 12 mounted in suitable bearings 13 and 14 and having a tapered cam 16 slidably mounted thereon which is adapted to be rotated 40 by the shaft 12 and to be axially slidable thereon by a manually operated lever 17 through a yoke 18 positioned within groove 20. Lever 17 is pivotally mounted within the housing 11 by shaft 19 and is adapted to be manually rotated 45 by any suitable means (not shown).

Shaft 12 is rotated in timed relation with the engine, one cylinder of which is shown at 21, by a shaft 22 mounted in the housing 11 by bearings 23 and having a gear 24 adapted to mesh with 50 an engine driven gear (not shown). The opposite end of shaft 22 is provided with gear 27 in mesh with gear 28 secured to shaft 12. The main portion of housing 11 is divided on a plane at right angle to the axis of shaft 12, the upper 55

and lower portions 29 and 31 respectively being secured together by a plurality of screws 32. Within the upper portion 29 are arranged a plurality of pump cylinders 34, the number of cylinders used being dependent on the number of cylinders in the engine upon which the pump is installed. Both portions 29 and 31 of housing 11 are preferably constructed of a light material such as aluminum in order to reduce the weight 10 for aircraft operation, and each of the cylinders 34 is preferably formed of a stronger material such as steel in order to have the cylinders impervious to fuel under high pressure. The cylinders are insertable from the inside of housing portion 29 and provided with a collar 36 for locating them therein, a nut 37 being threaded upon the upper end of cylinder for clamping it to the housing. Outlet valve 38, normally pressed against the fitting 39 by a spring 42, is preferably positioned in the upper end of the cylinder 20 and acts as a check valve to prevent fuel from being returned to the pump cylinder after it has been forced through the valve by the action of piston 43. A threaded cap 44 holds valve 38 and spring 42 in position, and a discharge conduit 46 is secured to the cap 44 by a nut 47. The upper end of spring 42 is preferably positioned in cap 44 by a novel washer 48, shown in Fig. 2, which has ears 49 and 51, the upturned ears 30 49 acting to space the washer 48 from the upper end of the recess holding the spring 42, and the downturned ears 51 being adapted to space the spring 42 from the side walls of the cap. It may be observed that in this construction the spaces 35 52 between adjacent ears of the washer act as passageways for gases accumulating within the outlet passage wherefrom they may readily pass upwardly through the outlet conduit 46 and the injection nozzle 54 to the engine cylinder 21.

40 Piston 43 is preferably provided with a reduced upwardly projecting portion 56 within which is a passage 57 adapted to communicate with a groove 58 formed in the side wall of the cylinder 34 whereby the cylinder gases are vented. Each 45 pump cylinder is fed by means of an inlet port 59 adapted to be uncovered by piston 43 toward the lower end of its stroke, the port being in communication with a downwardly extending passage 61 which is in communication with a central 50 supply chamber 62 formed in the body of the pump. The supply chamber 62 is fed from the main supply tanks 63 and 64 by means of an engine driven circulating pump 66 which draws its supply from one or the other tanks of 63 and 64 55 through conduit 67 or 68, valve 69 and conduit 71. The outlet from pump 66 is connected with the central supply chamber 62 by a conduit 73 and fitting 74.

60 As the fuel is delivered from pump 66 it passes upwardly through screen 76 to chamber 62 and through passage 61 to each of the individual pump cylinders, one of which is shown in Fig. 1 in position to receive a fuel charge. The central supply chamber 62 is preferably closed by a cover 77 secured thereto by screws 78 within which is a spring pressed relief valve 79 adapted to open at some predetermined pressure, whereby excess fuel from within the supply chamber 62 is returned to either of the main supply tanks 63 and 64 by a return conduit 81. A continuation of 65 return conduit 81 comprises a tubular member 82 secured to the cover 77 by fitting 84 and which tubular member projects downwardly to a point adjacent the screen 76, the purposes of which are hereinafter more fully described. An opening 75

is preferably formed in fitting 82 adjacent the upper portion of chamber 62 through which gases accumulating in the upper part of the chamber may readily pass through the outlet valve 78 to the main tank. 5

Pistons 43 are normally urged to their lower position by springs 92 and are provided with adjusting screws 93. Reciprocation of the pistons is accomplished by bell crank levers 94 pivotally mounted on the housing at 95, one end of which 10 contacts with adjusting screw 93 through roller 96 and the other end of which contacts with 15 slideable cam 16 by means of member 98 preferably having a rotatable spherical outer surface whereby friction is reduced to a minimum. 15 Groove 58, which is adapted to coincide with the lower portion of passage 57 formed in piston 43, is connected to the return conduit 81 by a 20 passageway 99 formed in the body of the housing 11 and preferably connected to the return conduit 20 81 on the return side of relief valve 79. The housing 11 is preferably provided with a plurality of 25 openings 101 through which the clearance between adjusting screws and bell cranks 94 may be observed and the adjustment varied if necessary. 25 The openings, if desired, may be normally closed by a transparent removable cover 102.

In the operation of the pump, the two-way valve 69 will be positioned in either of its operative positions, depending from which of the main 30 tanks it is intended to supply the fuel pump. In the position shown in Fig. 1, valve 69 is shown in the full line position as connecting tank 64 with the pump 66, from which fuel will be forced through passage 104, screen 76, passage 61, and 35 through inlet port 59 into the pump cylinder. It is preferred to maintain the pressure within chamber 62 at some predetermined pressure, for example three pounds, whereby when piston 43 reaches the position shown in Fig. 1, fuel will be 40 forced into the pump cylinder under pressure and the gases in the upper portion of the cylinder will be forced out of the cylinder and will pass downwardly through passage 57 and from thence outwardly through return conduit 81 to the 45 vented main supply tanks. Reciprocation of a piston 43 in the upward direction will first cut off communication between passages 57 and 99 and shortly thereafter will close port 59. The total 50 clearance space between the piston and the upper end of the cylinder is reduced by the annular body of fuel surrounding the projection 56 and the actual working clearance volume is of such value that at the upper end of the stroke all of the 55 gases and some of the fuel which has been forced into the pump cylinder above the top of the projecting portion 56 will be forced into the outlet passage 46. It will be readily seen in this construction that at the first stroke of the piston all the 60 gases within the cylinder will be forced into the discharge passage 46 and on the next intake stroke of the piston the cylinder will be completely filled with fuel and that any gases which collect within the cylinder because of absorption in the fuel may readily pass downwardly through passage 57 at each stroke of the piston and be returned to the tanks from which they may escape through 65 vent holes 106 and 107. The ratio of the total cylinder volume to the clearance volume, is preferably of a value that if no fuel be trapped by the 70 piston, the compression pressure of air alone is insufficient to open check valve 38. This is very desirable for it prevents the pump from forcing air to the engine after a failure of the fuel supply.

Although it is intended that screen 76 will pre- 75

vent the major portion of all foreign particles from reaching chamber 62 in ordinary constructions, this is ordinarily impossible to do completely, and for this reason tubular member 82 5 is projected downwardly to a point adjacent the screen. Pump 66 is preferably constructed with a capacity greater than that necessary to feed the individual pump cylinders and the excess will be forced through the tubular member 82 at 10 considerable velocity which will cause particles passing through the screen to be ejected past relief valve 79 and into the supply tanks.

Cam 16 is shown in Figs. 1 and 3 as positioned to give the maximum stroke of piston 43, but if 15 it should be desired to reduce the capacity of the pump, lever 17 is rotated in a counterclockwise direction, whereby cam 16 will be moved downwardly, and the tapered portion 108 will actuate the piston 43 at a less stroke for each rotation 20 of the cam. The leading surface 109 of cam 16 is preferably parallel to the axis of shaft 12, whereby the port 59 is closed by the piston at the same point in the cam cycle regardless of its 25 axial position. It is not essential that the cam be constructed in this manner, but it is preferred to do so in order to have the fuel injection occur at the same point in the engine cycle irrespective of the amount of fuel injected.

It may be readily observed from the above 30 description that an improved fuel pump has been provided in which provision is made for forcing fuel into the pump cylinder at each stroke thereof, and that the incoming fuel may force occluded gases from the cylinder because of the vented 35 construction of the cylinder and that because the vented gases are at no time subjected to pump pressure, the fuel may readily enter the cylinder. The reduced extension of the piston also acts 40 as a trap for the fuel, the selected clearance is such that there is no possibility of fuel not being forced to the engine cylinder because of compression of gases at the end of the piston stroke, and neither will the pump continue to force gases 45 to the engine when no fuel is present in the reservoir.

While a preferred embodiment of the invention has been illustrated and described, it is understood that this showing and description are illustrative only and that the invention is not limited to the 50 form shown or described, or otherwise, except by the terms of the following claims:

What is claimed is:

1. A fuel pump comprising a cylinder having an outlet in its top wall and a piston and a fuel 55 inlet arranged to be uncovered by said piston, means for forcing fuel to the cylinder, means for venting gases occluded in said cylinder during at least a portion of the time during which a fuel charge is forced to the cylinder, said venting 60 means including a reduced piston portion extending upwardly in said cylinder having an opening adapted to be periodically connected to the exterior of the cylinder venting means.

2. A fuel pump comprising a cylinder having an 65 outlet in its top wall, a piston and a fuel inlet arranged to be uncovered by said piston, means for forcing fuel to the inlet, a main supply tank, a return conduit from the pump to the tank and in open communication therewith, said cylinder 70 leaving an annular groove therein for conducting fuel leakage past the piston to the return conduit, and said piston having an upstanding reduced portion having a passage therein connecting said cylinder with the groove at the end of each 75 suction stroke.

3. A fuel pump comprising a substantially vertical cylinder having an outlet in its top wall, a piston and a fuel inlet arranged to be uncovered by said piston, means for forcing fuel to the inlet, a main supply tank, a return conduit from the pump to the tank and in open communication therewith, said cylinder having venting means therein for conducting fuel leakage past the piston to the return conduit, said piston having a reduced portion extending above the cylinder inlet 10 and provided with a passage adapted to connect the cylinder with the venting means while the inlet is uncovered by the piston.

4. A fuel pump comprising a substantially vertical cylinder having a piston, a fuel inlet and a fuel outlet, means for venting the cylinder at the termination of the inlet stroke comprising a second outlet passage controlled by the piston and having its entrance above the fuel inlet and below the first outlet, means for trapping a quantity of 20 fuel in the cylinder, and said pump having a clearance volume which is less than the volume of the trapped fuel.

5. A fuel pump comprising a cylinder having a piston, a fuel inlet and a fuel outlet, means for venting the cylinder at the termination of the inlet stroke, means for trapping a quantity of fuel in the cylinder, and said pump having a clearance volume which is less than the volume of the trapped fuel, said trapping means including a standpipe formed on said piston.

6. A fuel pump comprising a substantially vertical cylinder having a piston, a fuel inlet and a fuel outlet, said cylinder having a vented groove therein, said piston having a reduced upwardly extending portion provided with a conduit arranged to connect the groove with the interior of the cylinder during the suction stroke of the pump, said reduced portion defining with the cylinder an annular fuel space, the volume of which is greater than the clearance volume of the pump.

7. A fuel pump comprising a substantially vertical cylinder having a piston, a fuel inlet and a fuel outlet, said cylinder having a vented groove 45 therein, said piston having a reduced upwardly extending portion provided with a conduit arranged to connect the groove with the interior of the cylinder during the suction stroke of the pump, said reduced portion defining with the cylinder an annular fuel space the volume of which is greater than the clearance volume of the pump, said piston being arranged to uncover the fuel inlet and vent the cylinder concurrently.

8. A liquid fuel pump comprising a cylinder having a fuel inlet, a fuel outlet and a piston, a spring loaded check valve in the outlet the spring pressure on the valve being such that in the absence of liquid fuel the compression of gas in the pump is insufficient to open the valve, and means comprising an upstanding reduced piston portion having a venting opening therein for trapping liquid fuel in the cylinder at each suction stroke of the piston.

9. A liquid fuel pump comprising a cylinder having a fuel inlet, a fuel outlet and a piston, a spring loaded check valve in the outlet the spring pressure on the valve being such that in the absence of liquid fuel the compression of gas in the pump is insufficient to open the valve, said piston having a standpipe thereon adapted to trap liquid fuel at each suction stroke of the pump, and means for venting the standpipe during the suction stroke.
